UNITED STATES PATENT OFFICE.

JACOB BERLINER, OF HANOVER, GERMANY.

MICROTELEPHONIC APPARATUS.

SPECIFICATION forming part of Letters Patent No. 673,512, dated May 7, 1901.

Application filed December 4, 1900. Serial No. 38,711. (No model.)

To all whom it may concern:

Be it known that I, JACOB BERLINER, a subject of the King of Prussia, Emperor of Germany, residing at No. 24 Körnerstrasse, Hanover, Kingdom of Prussia, German Empire, have invented a new and useful Microtelephonic Apparatus, of which the following is a specification.

The object of my invention is to construct a microtelephonic apparatus which differs from those hitherto in use in that the part by which the apparatus is taken hold of contains a tapper-switch consisting of two parts, one of which closes, when depressed, the call-bell circuit, while the other closes the microphonic circuit on being pressed down. The sending-microphone and the receiver are connected to each other by an intermediate hollow piece, preferably of wood, having attached to it by means of a screw connected to the line a spring-blade, on the face of which are connected two strips of insulating material. The ends of the spring-blade are held by its elasticity away from contacts connected the one to the call-bell circuit and the other to the microphonic circuit. On the former end of the tapper being depressed the call-bell circuit is closed, while the depressing of the other end closes the microphone-circuit.

The preferred form of my invention is shown in the accompanying drawings, in which—

Figure 1 is a longitudinal section of the microtelephonic apparatus built according to my invention. Fig. 2 is a front view of same, and Fig. 3 a diagram showing the run of the circuits.

In the drawings, *a* is the microphone, *b* the telephone, and *g* a connecting member between the telephone and microphone.

While in the usual apparatus of this class a special push or knob independent of the apparatus has to be depressed in order to call

a correspondent, the call-bell contact-maker is according to the present invention so combined with the switching device for the microphone that the aforesaid tapper-switch consists of two parts, one of which closes, on being depressed, the call-bell circuit, while the other on being so acted on closes the microphone-circuit.

As shown in the drawings, the connecting member *g* is provided with a screw *d*, connected to the line and serving to fix to the connecting-piece a spring-blade *h*, to which are attached the insulating-pieces *e* and *f*, which on being depressed cause the ends of the spring-blade to contact with contact-screws *i* and *k*, fixed likewise to the connecting member *g*. When the tapper end *e* is depressed, the call-bell circuit is completed, while the depression of the other end, *f*, switches in the circuit of the microphone *a*. This appears on considering the diagram of circuits shown in Fig 3.

Having thus described my invention, what I claim is—

In a microtelephonic apparatus the combination with a connecting member between the receiver and the microphone, of a tapping-switch comprising a spring-blade fixed to the connecting member and connected to the line, a contact-screw opposite to the one end of the spring-blade and connected to the call-bell circuit and a contact-screw opposite the other end of the spring-blade and connected to the microphone circuit, substantially as described.

In testimony whereof I have hereunto set my hand in presence of two subscribing witnesses.

JACOB BERLINER.

Witnesses:

S. GOLDSCHMIDT,
G.G. FISCHER.
